The ornamental design for a portable ground power unit, as shown and described.

DESCRIPTION

FIG. 1 is a top perspective view of a portable ground power unit;

FIG. 2 is a front elevation view thereof;

FIG. 3 is a back elevation view thereof;

FIG. 4 is a right side elevation view thereof;

FIG. 5 is a left side elevation view thereof; and,

FIG. 6 is a top plan view thereof.

The broken lines in the drawings are included for the purpose of illustrating portions of the article that form no part of the claimed design.
